Ottawa

UNITED STATES PATENT OFFICE

IRA A. BURNETT, OF CHICAGO, ILLINOIS

TOOTHPRUSH HOLDER

Application filed May 9, 1928. Serial No. 276,220.

My invention relates to a device for holding brushes, as for example, tooth brushes, and more particularly to a holder of this type which is provided with means for permitting quick and efficient sterilization of the brush while in position on the holder.

Tooth brushes ordinarily are left lying about, or are hung up in the open air, with the result that they accumulate dust and micro-organism from the surrounding air, and especially while they are in a wet condition, form breeding ground for bacteria, moulds and other forms of microscopic life, thus rendering the brushes unsanitary.

Also, it is well recognized that the average tooth brush after a brushing of the teeth is laden with germs or bacteria which remain on the bristles and breed, if not properly sterilized before it is put away. It is apparent that a tooth brush has little value to clean the teeth, if containing bacteria before it is used, it will fail entirely to remove the bacteria on the teeth. The average individual fails to sterilize a tooth brush each time it is used, due to the trouble and effort of providing a sterilizer and the time spent in the operation. It is also considered troublesome to have such sterilizing means about when it is apparently easier to rinse the brush under the faucet and hang it in a rack.

An object of my invention is to provide a holder for tooth brushes which may be furnished with a vessel containing an antiseptic solution arranged to permit a quick immersion of the brush in the solution while the brush remains on the holder, without requiring the brush to remain in the solution any length of time. The vessel may be carried on the holder so as to permit it to be readily moved upwardly to immerse the head or bristle portion of the brush in the antiseptic solution and thereafter withdrawn to remain below the brush so as to allow the latter to drain any solution remaining on the brush back into the vessel.

A further object of my invention is to provide an arrangement above described, which will permit sterilizing of the brush while remaining on the holder, and which will prevent the brush, or its bristles, from remain-

ing immersed in the antiseptic solution long enough to affect the backing or the bristles. I find that there is a tendency, for a solution of sufficient strength to kill bacteria, to destroy the brush if in contact therewith any considerable time. My device is arranged to require the vessel to be brought upwardly over the bristles, and, when released, to drop back into position below the brush.

In order to apprise those skilled in the art how to construct and practice my invention, I shall now describe a preferred embodiment thereof in connection with the accompanying drawings which form a part hereof.

In the drawing: 65
Figure 1 is a perspective view of the improved tooth brush holder; and

Fig. 2 is a vertical sectional view of the same, showing the vessel raised to submerge the bristles of the tooth brush in the antiseptic solution. 70

A holder embodying my invention may comprise a bracket designated as A adapted to be attached to a vertical surface on or adjacent to a medicinal cabinet, or other portion of the side wall, so as to keep the tooth brush in a handy place and ready for use. 75

Bracket A is preferably made of sheet metal, or other like material, capable of being readily stamped and formed whereby to provide a wall plate 1 furnished with apertured ears 2 for receiving the fastening means attaching the device to a mounting, a horizontally forwardly extending bent portion 3 and a vertical portion 4 adapted to be provided with means for movably receiving a tooth brush in a vertical position. 80

Such means may comprise a spring clip 5 at the upper end of vertical portion 4, which clip 5 is fixed at 6 to the portion 4 and cooperates at its upper end with a U-strip 7 for yieldably holding the upper end of a tooth brush in position. The manner in which this is accomplished may be seen in Figs. 1 and 2 wherein the tooth brush is illustrated in 85 dotted lines.

A depending supporting member 8 extends downwardly through horizontal portion 3 whereby to carry at its lower end a rest 9, against which the extreme tip of the tooth 100

brush at the head portion engages. Guiding arms 10 may be furnished midway along depending member 8 for guiding the intermediate portion of the tooth brush. Member 8

5 may extend upwardly through the horizontal portion as described, and be secured to the back of the vertical portion, as illustrated in Fig. 2. A perforated cup 12 is secured to the extreme lower end of member 8.

10 A depending rod 13 is provided at the rear of depending member 8, this rod 13 being suitably secured to horizontal portion 3. An elongated bearing sleeve 14 is adapted to slide along rod 13. A threaded ring 15 may be attached to, or otherwise made integral with, bearing sleeve 14 so as to removably receive a container or vessel 16 adapted to contain an antiseptic solution 17. It will be observed that vessel 16 is threaded at its upper end

15 into ring 15. The purpose of permitting vessel 16 to be readily removable is to permit the solution to be readily changed when desired.

By referring to Fig. 1, it will be seen that perforated cup 12 serves as a cover for the vessel when the same is in its lower position as illustrated in this figure. A pin 18 is provided at the lower end of rod 13 to act as a stop so as to limit the downward movement of sleeve 14. Normally, vessel 16 will be in

20 the position shown in full lines in Fig. 1. Perforated cup 12 will lie directly over the mouth of vessel 16, being however of slightly smaller diameter to permit this vessel to move upwardly and over the same, whereby to submerge perforated cup 12 in the solution. Upward movement of vessel 16 also submerges the tooth brush, or the bristles, as noted in

25 Fig. 2, whereby to permit complete and efficient sterilization of the bristles. Such upward movement of vessel 19 may be readily obtained by the person merely gripping the vessel and sliding it upwardly along rod 13. After a complete immersion of the bristles in the antiseptic solution, the individual may

30 allow this vessel to move downwardly again, and, if the brush has just been used, it is allowed to remain on the holder and drain any of the solution on the bristles back into the vessel. The means provided to hold the

35 tooth brush on the holder advantageously suspends the tooth brush in a vertical position over the mouth of vessel 16. Rest 9 is arranged to prevent the lower end of the

40 backing of the tooth brush from contacting with the cup 12 whereby in the absence of such contact the brush will be allowed to immediately drain the solution clinging to the bristles back into the vessel and be dried.

45 I have found that it is often desirable to sterilize the brush before use after remaining exposed in the air on the holder. This can be readily accomplished by bringing the vessel 16 upwardly along rod 13 to immerse the

50 bristles in the antiseptic solution. The brush

can then be removed from the holder and rinsed under the faucet so as to be in a suitable condition for use on the teeth. I have also found it to be desirable to sterilize the brush after use so as to immediately kill the

55 bacteria removed by the brush from the teeth. Hence, the brush may be immersed immediately after placed on the holder, the brush remaining on the holder thereafter until again used.

60 Vessel 16 may be of any material, but I preferably employ glass or other transparent substance which will permit a person to observe the amount of antiseptic solution in the vessel. I also contemplate providing a marking to indicate the level at which the solution should be kept in order to completely immerse the bristles of the brush when the vessel is moved upwardly along rod 13. Such markings may be in the form of an indicator

65 cut into the glass or the material of vessel 16.

70 Without further elaboration, the foregoing will so fully explain the gist of my invention, that others may, by applying current knowledge, readily adopt the same for

75 use under varying conditions of service, without eliminating certain features, which may properly be said to constitute the essential items of novelty involved, which items are intended to be defined and secured to me by

80 the following claims.

I claim:

1. A holder for tooth brushes and the like comprising a bracket adapted to be attached to a vertical surface and having an upright portion associated with means for removably holding a tooth brush thereon, and a vessel adapted to contain an antiseptic solution movably carried by said bracket for immersing the head of the tooth brush in said solution.

2. A holder for tooth brushes and the like comprising a bracket adapted to be mounted substantially vertically and having means associated therewith for removably receiving a tooth brush thereon, and a liquid vessel provided with relative movement for immersing the head of the tooth brush in said vessel while carried on said bracket.

3. A holder for tooth brushes and the like comprising a bracket having means removably carrying a tooth brush in a vertical position, a vessel adapted to contain an antiseptic solution removably carried by said bracket, and a mounting on said bracket for said vessel providing for relative movement between said bracket and said vessel whereby the head portion of the tooth brush may be momentarily immersed in said solution while in position on said bracket.

4. A holder for tooth brushes and the like comprising a bracket having means removably carrying a tooth brush in a vertical position, a vertically positioned rod carried by said bracket in close proximity to the tooth

brush, and a vessel adapted to contain an antiseptic solution movable along said rod for immersing the head portion of the tooth brush in said solution.

5 5. A holder for tooth brushes and the like comprising a bracket having means for removably carrying a tooth brush thereon, said means including a spring clip for receiving the handle end of said brush and a depending member with a perforated cup at the lower end over which the head portion of said brush lies, a rod extending downwardly on said bracket, and a vessel adapted to contain an antiseptic solution movable along said rod to immerse the head portion of said brush in said solution, said perforated cup normally serving as a cover for said vessel and as a drain for solution remaining on said brush after immersed in said vessel.

10 6. A holder for tooth brushes or the like comprising a bracket having means for removably carrying a tooth brush thereon, said means including a spring clip at the upper end for receiving the handle end of said brush and a depending member with a rest at its lower end for receiving the head portion of said brush, a depending rod on said bracket disposed at the rear of said depending member, a vessel adapted to contain an antiseptic solution movable along said rod, and a perforated cup carried on said depending member below said rest, said cup normally serving as a cover for said vessel.

15 7. A holder for tooth brushes or the like comprising a bracket having means for removably carrying a tooth brush in a vertical position, a rod depending from said bracket, a sleeve movable along said rod, a forwardly extending ring on said sleeve, and a vessel adapted to contain an antiseptic solution for said tooth brush removably carried by said ring.

20 8. A holder for tooth brushes or the like comprising a bracket having a vertical mounting plate, a forwardly extending horizontal portion and a vertically extending portion above said horizontal portion, means on said vertically extending portion for removably carrying a tooth brush on said bracket, and means on said horizontal portion for movably carrying a container, said container having an antiseptic fluid therein for sterilizing said brush while carried by said means.

25 55 In witness whereof, I have hereunto subscribed my name.

IRA A. BURNETT.
